UNITED STATES PATENT OFFICE.

CARL G. JANSON AND CHARLES J. BRAUN, OF OAKLAND, CALIFORNIA.

BUNK.

1,349,962.

Specification of Letters Patent. Patented Aug. 17, 1920.

Application filed July 9, 1918. Serial No. 244,029.

To all whom it may concern:

Be it known that we, CARL G. JANSON and CHARLES J. BRAUN, citizens of the United States, residing at Oakland, in the 5 county of Alameda and State of California, have invented certain new and useful Improvements in Bunks, of which the following is a specification.

This invention is an improved bed particularly useful on ships and in camps. The 10 bed is simple, cheap and sanitary and will fit into awkward spaces.

The invention is illustrated in the accompanying drawings which form a part of 15 this specification and the appended claims.

Referring to the drawings:

Figure 1 is a side elevation of the bed.

Fig. 2 is a plan view of the bed.

Fig. 3 is an end elevation of the bed.

20 Fig. 4 is a plan view of the supporting means for the mattress supporting frame. Figs. 5, 6 and 7 are respectively a side elevation, an end elevation and a plan of portions of a modified form of bed.

25 In the drawings, 1 and 2 indicate a head and foot post, on the bottom and top of which collars 3 are turnably mounted, said collars having flanges 4 which may be secured to the floor and ceiling to secure the 30 posts in position to support the bed. Set screws 4' are provided in the collars 4 to prevent turning of the posts.

Angle iron supports 5 and 6 are bolted midway between their ends one above the 35 other to the inside of posts 1 and 2 by bolts 7 and 8, the flanges 9 of which supports extending inwardly from the posts and the ends of the flanges 10 of said supports being provided with notches 11. The supports 5 and 6 are maintained in horizontal 40 position by angular stays 12 which are riveted at their corners to the posts 1 and 2 and at their ends to the flanges 10 of said supports. Lower and upper mattress frames 13 and 14 are provided for sustaining the lower 45 and upper mattresses of the bed. Said mattress frames include end angle members 15, having inwardly extending flanges 16 secured to the ends of the side rods 17 of the 50 frame, and downwardly extending flanges 18 which rest upon the flanges 9 of supports 5 and 6 respectively and have pins 19 extending therefrom which fit in the notches 11, whereby the mattress frames are supported 55 properly on the bed posts 1 and 2. Mattress springs 20 are secured at their ends

to the flanges 16 of the end frame members 15. Guards 21 are pivotally mounted on the outer side rods 17 of the mattress frames at the head of said frames and are normally held in upright position by hooks 22 pivoted to the posts 1 and 2 and eyes 23 on the keepers which are engaged by the hooks. When the hooks are disengaged from the eyes, the guards swing down from the rods 17 and 60 the mattress frames 13 and 14 may be lifted off the supports 5 and 6. When the mattress frames are removed from the supports 5 and 6, the set screws 4' may be loosened and the posts turned into such a position 65 that the supports 5 and 6 will be out of the way.

In the modification shown in Figs. 5, 6 and 7, one end of the guard 21 is pivoted at 70 25 to the outside of the head end frame member 15 and engages the end of the support 5 on the post 1 whereby the guard is maintained in upright position when the bed is assembled. When the mattress frame is removed from the supports 5 the guard 75 80 may swing down by gravity. The ends of the supports 5 are maintained rigidly in position by braces 26, secured at their respective ends to the bed posts below said supports and to brackets 27 which are secured 85 to the ends of said supports. Head rail 28 and foot rail 29 are respectively secured at their ends to the inner side of the flanges 10 of the head and foot supports 5. Said head 90 and foot rails extend horizontally above the supports 5 and the ends of the mattress frame and downwardly at their ends which are secured to the supports. The ends of the flanges 10 of the supports 5 are bent inwardly to rest against the ends of the mattress frame and to provide a space between the ends of said mattress frame and the flanges 10 of supports 5 to receive the ends 95 of the head and foot rails.

Having described our invention, we claim 100 as new and desire to secure by Letters Patent:

1. A bed of the kind described comprising a single head-post and a single foot-post, transversely extending supporting members 105 one secured at an intermediate portion thereof to each post, a pair of brace arms secured to each post, the arms of each pair having connection respectively with the opposite ends of a supporting member on the post, a 110 mattress frame adapted to extend between the posts and to rest on said supporting

members, a guard hingedly connected to a side of the mattress frame, a hook element loosely connected to one of said posts and engageable with the guard to maintain it in upright position.

2. A bed of the kind described comprising a single head-post and a single foot-post, transversely extending supporting members one secured to an intermediate portion thereof to each post, a pair of brace arms secured to each post, the arms of each pair having connection respectively with the opposite ends of the supporting member on the post, an intermediate portion of said supporting members between their extremities having a flange inwardly projecting from its lower edge portion, the extremities of said supporting member being offset inwardly and having notches in the upper edges of said offset portions, a mattress frame to extend between said posts and to rest upon the flanges of said supporting members, and projections extending from the mattress frame and adapted to engage in the notches of the supporting members to maintain the frame against accidental displacement.

3. A bed of the kind described comprising a single head-post and a single foot-post, horizontal supporting members, one secured

at an intermediate portion thereof to each post, a head-rail and a foot-rail rigidly mounted on said supports, respectively, an inwardly projecting flange extending from each of said supporting members, a mattress frame adapted to extend between said posts and to rest upon said flanges, a pair of brace arms secured to each post at a point distant from said supporting members, and outwardly projecting extensions on the ends of the supporting members, the brace arms of each pair extending within the plane of the post and having connection with said outward extensions of the supporting members on said posts.

4. A bed of the kind described comprising a single head-post and a single foot-post, transversely extending supporting members one secured at an intermediate portion thereof to each post, respectively, a pair of brace arms secured to each post, the arms of each pair having connection respectively with the opposite ends of a supporting member, and a mattress frame adapted to extend between said posts and to rest on said supporting members.

In testimony whereof we affix our signatures.

CARL G. JANSON,
CHARLES J. BRAUN.
